CLAIM

The ornamental design for a cover for cooking pot with handle as shown and described.

DESCRIPTION

FIG. 1 is a top, front and left side isometric view of a first embodiment of a cover for cooking pot with handle showing my new design;

FIG. 2 is a bottom, rear and left side isometric view thereof;

FIG. 3 is a top plan view thereof;

FIG. 4 is a bottom plan view thereof;

FIG. 5 is a front elevation view, the rear elevation being identical thereto;

FIG. 6 is a left side elevation view, the right side being identical thereto;

FIG. 7 is an enlarged detail view of portion 7 shown in FIG. 6;

FIG. 8 is a cross-sectional view taken along line 8-8 of FIG. 3;

FIG. 9 is a cross-sectional view taken along line 9-9 of FIG. 3;

FIG. 10 is a top, front and left side isometric view of a second embodiment of a cover for cooking pot with handle showing my new design;

FIG. 11 is a bottom, rear and left side isometric view thereof;

FIG. 12 is a top plan view thereof;

FIG. 13 is a bottom plan view thereof;

FIG. 14 is a front elevation view, the rear elevation being identical thereto;

FIG. 15 is a left side elevation view, the right side being identical thereto;

FIG. 16 is an enlarged detail view of portion 16 shown in FIG. 15;

FIG. 17 is a cross-sectional view taken along line 17-17 of FIG. 12; and,

FIG. 18 is a cross-sectional view taken along line 18-18 of FIG. 12.

The broken lines show portions of the cover for cooking pot with handle and form no part of the claimed design. The

(Continued)

dot-dot-dash broken lines illustrate the border of the enlarged detail views and form no part of the claimed design.
